Des. 820

By E. W. & J. A. Blake of New Haven, Conn.
Letters Patent. N° 820. Dated Aug. 5th 1856.

The schedule referred to in these Letters Patent and making part of
the same.

To all persons to whom these Presents shall come.

Be it known that we, Philo Blake, Eli W. Blake, and John A. Blake, of New Haven, in the County of New Haven, and State of Connecticut, have invented or produced a new, useful and ornamental configuration or Design for a "Drawer Pull", and we do hereby declare that the same is fully described and represented, in the following specification and the accompanying drawings, of which,

Figure 1, is a front view of

Figure 2, a rear elevation

Figure 3, an end view, and

Figure 4, a transverse section of it.

The design in question is composed of an elliptical oval shaped ring A, and a quadrantal ellipsoidal or egg shaped projection B, extended from the upper half of said ring as shown in the Figures, the edge or rim, a, being so raised above the plane of the ring A, as to enable a person to pass the fingers of his hand between it and the ring and up underneath the part B, when the whole article is placed against and affixed to a plane surface so that the ring A, shall be laid flatwise in contact therewith, and be fastened thereto.

by screws, extended through holes b, b, arranged as shown in Figure 1&2.

While the lower part of the ring A, serves to resist the strain or leverage that is brought to the article when it is fastened to the front side of a drawer and is pulled forward by hand of a person, the space within the ring, combined with that of the cavity c, of the part B, not only increases the space for the reception of the hand or fingers, but causes the whole to be lighter in weight than would be the case were the space within the ring filled with metal.

Besides possessing beauty of form, the article with such a configuration is rendered useful in many respects.

We claim the above described and represented new ornamental configuration or design for a drawer pull.

In testimony whereof we have hereunto set our signatures this eleventh day of June A. D. 1856.
